HORATIO L. PEIRCE, OF TAUNTON, MASSACHUSETTS.

Letters Patent No. 95,261, dated September 28, 1869.

IMPROVEMENT IN TRAVELLER FOR SPINNING-RING.

The Schedule referred to in these Letters Patent and making part of the same.

To all whom it may concern:

Be it known that I, HORATIO L. PEIRCE, of Taunton, in the county of Bristol, and State of Massachusetts, have invented a new and improved Ring-Traveller; and I hereby declare the following to be a full, clear, and exact description thereof, reference being had to the accompanying drawings.

To enable others skilled in the art to make and use my invention, I will proceed to describe it fully and particularly.

In order that the description may be as clear and explicit as possible, I will describe the manner hitherto generally pursued in making ring-travellers, and the form and shape given them, and the objections against this form or shape.

A flattened wire or metallic ribbon, generally of steel, with rounded edges, and of the requisite width and thickness, is obtained and cut perpendicularly to the longitudinal axis of the ribbon, into the desired or required lengths, and bent around a mandrel of the proper form to give the requisite size and form to the ring-traveller.

This form or shape is that described and represented in the annexed drawing, fig. 3, in which it will be seen that the points *a a*, of both sides of the ring-traveller, are at right angles to the sides, caused by the manner in which the wire or ribbon is cut off, as above described.

There are several objections to this form of ring-traveller, among which are the following:

The traveller is sprung upon the ring with much difficulty.

It is difficult to give them a desirable temper or hardness, and yet leave them soft enough to be readily sprung upon the ring.

The square corners interfere with the slipping of the yarn under the ring-traveller by the operators or spinners. These square corners soon wear into the ring on the inner and under side, unevenly, frequently caus-

ing an unsteady motion, which is liable to break the yarn. As these corners wear off, the draught on the yarn is increased.

To obviate these and other apparent difficulties, I have devised a ring-traveller of the form or shape described in Figures 1 and 2.

I use the same sort of flattened metallic wire or metallic ribbon, but instead of cutting it into pieces, the ends of which are perpendicular to the longitudinal centre of the ribbon, I clip the corners off, giving to the ends a rounded or elliptical or other desirable shape, as shown at *b*, by which the objectionable corners are avoided in the ring-traveller.

The advantages attending the use of ring-travellers of this form are, in part, the following:

First, they are put on to the ring much easier.

Second, they can be made of better temper, or harder than those of the old form.

Third, they wear upon the ring more uniformly.

Fourth, they can be made heavier, and will consequently wear longer.

Fifth, they secure a more uniform draught on the yarn.

Sixth, the yarn can be slipped under them more easily.

Having described my invention,

What I claim, and desire to secure by Letters Patent, is—

The rounded formation, in a ring-traveller made of a flat metal strip, as described, of the bent ends, which hold the traveller upon the ring, substantially as and for the purposes shown and set forth.

In testimony whereof, I have signed my name to this specification, before two subscribing witnesses.

HORATIO L. PEIRCE.
